UNITED STATES PATENT OFFICE.

GEORGE IRVING WAUGHTAL, OF MASON CITY, IOWA.

HARROW.

SPECIFICATION forming part of Letters Patent No. 357,254, dated February 8, 1887.

Application filed November 24, 1886. Serial No. 219,809. (No model.)

To all whom it may concern:

Be it known that I, GEORGE IRVING WAUGHTAL, a citizen of the United States, residing at Mason City, in the county of Cerro 5 Gordo and State of Iowa, have invented a new and useful Improvement in Harrows, of which the following is a specification.

My invention relates to an improvement in harrows; and it consists in the peculiar construction and combination of devices, that will be more fully set forth hereinafter, and particularly pointed out in the claims.

In the drawings, Figure 1 is a perspective view of a harrow embodying my improvements. Fig. 2 is a detail sectional view of the same, taken on the line xx of Fig. 1. Fig. 3 is a detailed horizontal sectional view taken on the line yy of Fig. 2. Fig. 4 is a similar view taken on the line zz of Fig. 3. Fig. 5 is a perspective view of my improved harrow when formed of a limited number of sections. Fig. 6 is a detail of the front coupling of the harrow-sections. Fig. 7 is a detail view of the rear coupling.

25 A represents a series of harrow-sections, each of which comprises a pair of bars, B and C, which are rigidly secured together at an angle of about seventy degrees.

D represents a series of clamp-plates, which 30 are bent at an angle corresponding to that of the sections A, and the said plates are bolted to the inner sides of the said sections at the elbows formed at the meeting ends of the bars B and C. The upper and lower sides of the 35 angle-plates D are provided with right-angled outwardly-extending flanges E, which bear upon the upper and lower sides of the bars B and C. To the front end of each section, on the upper side thereof, is secured a metallic 40 strap, F, the front end of which is provided with a transverse eye, G.

H represents a link-arm, which is pivoted to each section A by a bolt, I, that passes through openings made in the rear ends of the link-bar 45 and through the eyes G of the strap.

K represents an evener or draft-bar, which is provided with a series of bolts, L, that pass through transverse openings made in the said bar and have nuts M on their outer threaded 50 ends. The lower ends of the bolts L are provided with eyes N, which are adapted to be

inserted between the bifurcated front ends of the links H, and bolts O are then passed transversely through openings which are made in the front ends of the links H, and also through 55 the eyes G of the bolts L. By this construction it will be readily understood that each harrow-section is flexibly connected to the evener or draft-bar, so that the said harrow-sections are free to move laterally, and also 60 vertically, independent of each other. The harrow-sections are provided with the usual harrow-teeth, P, which extend through vertical openings that are made in the bars B and C.

To the rear end of each harrow-section, on 65 the outer side thereof, is bolted a metallic strap, R. The said straps have their rear ends projecting beyond the rear ends of the harrow-sections, and are provided with the reduced necks S and the heads T. The front end of 70 each strap R, on one side thereof, and at its upper and lower edges, is provided with a pair of laterally-extending lugs or ears, U. Bolts V pass through vertical central openings which are made in the said ears.

75 W represents a series of connecting-rods, which are each provided at one end with an eye, W', and at the opposite end with a loop, W². Each of the said connecting-rods has its eye W' pivoted on the bolt V of one of the 80 straps R, and the link W² engages the neck S of the strap R of the adjacent harrow-section. The heads T prevent the loops W² from becoming disengaged from the necks S. It will be observed that a considerable space is left between each pair of ears U and the eye W' of the connecting-rod, so that the latter is free to play vertically between the said ears, and that owing to the loops W² the rear end of each harrow-section is free to vibrate laterally on 90 the connecting-rod, and thereby the independent movements of the harrow-section before mentioned are not impaired by having their rear ends connected together by the rods W.

Owing to the angles at which the harrow sections or bars are bent, the latter are maintained in a horizontal position on the ground, with the points of their teeth engaging the soil.

The operation of my invention is as follows: When the harrow is drawn across a field, its 100 independently-movable sections conform to the inequalities of the ground, and thereby all

of the harrow-teeth are kept at work and the soil is thoroughly pulverized. In the event that a stump, stone, or other obstruction is encountered, one or more of the harrow-sections which come in contact therewith will be caused to rise or to move laterally, so as to clear the obstruction without disturbing the remaining harrow-sections, which will continue at work.

10 Having thus described my invention, I claim—

1. In a harrow, the combination of the draft-bar or evener and the harrow-sections, each formed of a single bar bent at a suitable angle 15 and provided with harrow-teeth, the said harrow-sections being flexibly connected together, and each flexibly connected to the draft-bar or evener, substantially as described.

2. The combination of the draft-bar or 20 evener, the links H, swiveled to the same, and the harrow-sections pivoted separately to the rear ends of the said links, the rear ends of the said harrow-sections being flexibly connected together, substantially as described.

25 3. The combination of the draft-bar or evener, the bolts L, attached thereto and free to turn therein, the said bolts being provided with the eyes N, the links H, having their front ends pivoted to the eyes of the bolts, and the independent harrow-sections having their front ends pivoted to the rear ends of the links H, substantially as described.

4. In a flexible sectional harrow, the com-

bination of the harrow-sections A, having their front ends flexibly connected together, 35 the rear ends of the said sections being provided with the ears U and the projecting heads T, and the rods W, having their inner ends pivoted on bolts between the ears U and free to play vertically thereon, the outer ends 40 of the said rods W having the loops W², to engage the heads of the adjacent harrow-sections, for the purpose set forth, substantially as described.

5. In combination with the draft-bar or 45 evener, the harrow-sections independently pivoted thereto, each harrow-section having at their outer ends rods W, provided with loops W², and the straps R, having heads T and the neck S, as set forth.

6. In combination with the draft-bar or evener, the harrow-sections independently pivoted thereto at their front ends, and rods W, pivoted to one section and coupled to the adjacent section, said rods having a vertical 55 movement, the harrow-sections being adapted to slide laterally for a limited distance independently of the rods.

In testimony that I claim the foregoing as my own I have hereto affixed my signature in 60 presence of two witnesses.

GEORGE IRVING WAUGHTAL
